United States Patent Office

Des. 188,891
Patented Sept. 27, 1960

188,891

PILLOW

William M. Emery, 44 Pittsford Way,
New Providence, N.J.

Filed June 17, 1959, Ser. No. 56,393

Term of patent 14 years

(Cl. D3—9)

FIG. 1

Figure 1 is a plan view of a pillow showing my new design; and Figure 2 is an edge view looking from the top of Figure 1.

The face not shown is substantially the same in appearance as the face shown in Fig. 1.

I claim:

The ornamental design for a pillow, as shown and described.
